UNITED STATES PATENT OFFICE.

CARROLL C. FIGGE, OF CHICAGO, ILLINOIS.

FLASHING.

Application filed January 26, 1922. Serial No. 531,847.

To all whom it may concern:

Be it known that I, CARROLL C. FIGGE, a citizen of the United States, residing at Chicago, in the county of Cook and State of Illinois, have invented certain new and useful Improvements in Flashing, of which the following is a specification.

This invention relates to a flashing for use at the edges of roofs, decks, floors, and the like, and the principal object of the invention is to provide a construction which has a greater tensile strength than the flashings, other than those of metal, in use at the present time, and having a greater life than the flashings commonly used either when made of metal or other material, as commonly employed. Another object of the invention is to provide a flashing which is held securely in place in a ragger joint and tends to become more firmly wedged therein if a tension is applied to the flashing proper. Another object of the invention is to provide a flashing of this kind in strip form with a continuous or sectional metal holding clip so that the flashing can be easily applied and secured in place. Other objects will appear hereinafter.

In the accompanying drawings, Fig. 1 is a plan view of a flashing constructed in accordance with the principles of this invention and applied to the edge of a roof; Fig. 2 is a section taken on the line 2—2 of Fig. 1; Fig. 3 is a section taken on the line 3—3 of Fig. 1; Fig. 4 illustrates a flashing with a pair of holding plates and a plurality of flashing strips; Fig. 5 illustrates a modified form of flashing in place; Fig. 5^a is an enlarged view of a portion of the modified form of flashing shown in Fig. 5; Fig. 6 is a section taken on the line 6—6 of Fig. 3; Fig. 7 illustrates a metal strip of different form; and Fig. 8 shows this strip applied to a wood base board.

It is the present practice to make a flashing either of metal in one or two pieces which quickly deteriorates due to the exposed position and the action of the elements, or to use a felt paper or fabric impregnated with bitumen, which has very little tensile strength, which may be somewhat brittle and will readily break. The present invention proposes a flashing which is made up of a fabric of considerable tensile strength, usually in several layers and attached to a metal clip by which it is readily and firmly secured in a ragger joint. Another feature

of difference is that in the flashings commonly used they are built up as applied, whereas the present invention is intended only as a complete flashing, separately built up in lengths and needing only the direct application where they are applied.

Referring more particularly to the drawings, this flashing is applied to a brick wall 1 of ordinary construction which extends above or at the side of a roof or deck 2. The difficulty is to make a fluid-tight joint in the angular corner between the roof and the brick wall. The roof itself has a covering 3 which extends up to the edge of the wall, and this covering may be of any desired or suitable construction, usually consisting of asphalt roofing, of various kinds, in sufficient thickness to form a thoroughly waterproof covering.

The flashing of the present invention comprises a plurality of strips 4 and 5 of woven material such as canvass or the like, which has considerable tensile strength and is also of such a character that it will become saturated with and hold a quantity of coating of bitumen such as tar or asphalt paint. These strips of material are secured together along their corresponding edges and to a clip 6 preferably composed of a metal bend in the form of a V with the edges thereof curving slightly outward, the impregnated strips 4 and 5 being secured thereto by metal tongues 7 bent outwardly from the strip 6 and through the strips 4 and 5 securing them in place against the metal strip 6.

Instead of having a continuous metal strip 6, there may be a plurality of sectional strips of this kind at intervals, as indicated in Fig. 1, and of course the flashing will be supplied in lengths which will overlap at their extremities to make a fluid-tight joint.

Instead of having one metal strip 6, the fabric strips may be secured together by a pair of metal strips 8 and 9 connected by rivets 10, as shown in Fig. 4, and the flashing proper may consist of outer woven fabrics 4 and 5 with an inner layer 11 of a more yielding material, such as a felt material, either paper or fabric. To further strengthen either of the fabrics 4 or 5 a net work or screen 12 of woven wire fabric may be incorporated in the strip or as a part of the flashing.

In applying a flashing of this kind a

raggle is made between two adjacent courses of brick at a slight height above the surface of the floor 2, the connected edges of the flashing strips including the metal strip 6 are inserted in the raggle with the strips lying at the bottom thereof, and a cement 13 fills up the joint made by the raggle between the bricks. The width of the metal strip is such that its edges preferably engage the adjacent brick courses, and it may be slightly compressed to insert it in the raggle, the object being that if any attempt is made to pull it by means of the strips 4 or 5, the opposite edge of the strip 6 will be pressed against the brick surface tending to hold it in. Thus the flashing would be held in place without the cement 13 by the resiliency of the strips, but the cement is also included and acts as an anchor as well as a preservative.

The depending portions of the strips 4 and 5 lie against the wall and may be secured to each other and to it by an asphalt paint, the lower ends of these fabric strips preferably overlap so that the inner one is attached to the edge of the roof covering 3, as shown in Fig. 2, and the outer one is secured to the lower fabric strip 5, overlaps it and its overlapping edge is also secured to the covering 3.

As shown in Fig. 5, the under layer of fabric extends below the edge of the covering 3, while the outer fabric layer 4 extends on top of the covering. In the flashing shown in this figure the layer 11 also overlaps the covering 3, and the connected edges of the flashing fabrics are secured together by stitches 14 of wire or metal clips. Thus it is possible to dispense with the spring strips 6 if a holding cement 13 is employed but the metal strip construction is preferable.

This flashing when constructed of two or more plies of fabric, secured in a raggle point with the self-locking spring clip and the raggle then filled with an asphalt cement, will be more lasting than an all metal flashing and will be considerably less expensive. The fabric has a high tensile strength with the property of withstanding abuse of a marked degree, and when impregnated with its own weight, or more, of a bitumen, will last indefinitely if properly applied. When this flashing is properly applied water runs over the lap or crevice and not into it. Even if the cement 13 becomes loose the flashing will remain in place and will be water-tight. Owing to the toughness of the fabric, protection is afforded to that section of the roofing which constitutes the bend from the deck to the wall. It is at this point that good roofs frequently leak owing to the use of inferior flashings.

The way the flashing lies in the raggle

depends upon how it is gouged out and the metal strip can be bent as desired to fit the raggle. The metal strip 6 may have one flat edge 15, as shown by Fig. 7, which lies parallel with the lower course of brick and with the other or outer edge bent or rounded upwardly therefrom, the extremity 16 of the outer edge being bent sharply outward so that it will engage the course of brick at the top of the raggle. The holding cement 13 is inserted in the outer edge of the raggle to hold the flashing in place as before and any outward pull upon the fabric tends to engage the bent edge 16 with the upper course of brick thereby binding the flashing more securely in position.

The form of flashing shown in Fig. 7 is particularly adaptable for use in connection with roof constructions where there is a wooden base board as well as a brick wall in which the flashing is to be inserted. As shown by Fig. 8 the metal strip 6 is bent substantially at right angles and the bent edge 16 of the metal strip is driven into a base board 17 by a fastening device 18 which holds it securely in place and makes a joint with a base board resembling a raggle in which there is no opportunity for any moisture to get beyond the flashing. It should be understood that in applying flashing of this kind the fabric strips are usually loose from each other before the flashing is applied, but they may be secured to each other, to the wall or to the roof deck, usually by means of a hot swabbing of bitumen paint or the like, which holds the fabrics together and makes them additionally water proof. It is obvious that the metal strips may be furnished flat and bent to any desired shape corresponding to the place where the flashing is to be applied.

I claim:

1. A flashing comprising strips of fabric secured together along one edge only of each fabric independent of its attachment to a wall.

2. A flashing comprising strips of fabric secured together along one edge, and a metal clip to which this edge of the flashing is permanently attached before its application to a wall.

3. In a flashing, a bent metal strip and a plurality of fabrics permanently attached at one edge thereto independent of its application to a wall.

4. A flashing comprising a fabric and a bent metal clip permanently and independently attached along one edge thereto and adapted to be inserted in a raggle for holding the flashing in place.

5. In a flashing, a strip of fabric coated with bitumen, and a bendable strip attachable along one edge of the fabric prior to its insertion in an open horizontal slot and adapted to engage the wall thereof to lock

itself in place therein against an outward pull on the fabric.

6. The combination with a fabric flashing, of a spring strip therefor adapted to be independently inserted in a raggle for holding the fabric in place.

7. In a flashing, a plurality of fabric plies of variant widths, and a spring metal strip attached to the plies along one edge thereof prior to insertion in a raggle.

8. In a flashing, a spring holding means for insertion in a raggle, and a plurality of fabric plies attached thereto along one edge prior to its insertion, the plies being of different widths one overlapping the others.

9. In a flashing, a spring holding clip, and a plurality of plies attached thereto prior to the insertion or use of the clip and one of the plies being reenforced to have a higher tensile strength.

10. In a flashing, a plurality of fabric plies adapted to overlap each other at the edge of a roof, and a resilient strip for attaching the plies together at their opposite edges prior to the application of the flashing, the strip and fabric being insertable in a raggle above the roof, and means for holding the strip and fabric in place in the raggle.

11. The combination with a brick wall, and a deck adjacent thereto, of a flashing comprising a plurality of plies of fabric and a spring metal strip permanently attached along one edge of the fabrics, the strip being adapted to be sprung in place in a raggle joint between the bricks, and a cement covering the strip and filled in the joint for holding the flashing in place.

12. A brick wall flashing comprising a fabric strip, a spring metal clip previously attached thereto along one edge of the strip and being of a V-shape, the ends of which are curved outwardly so that it may be inserted and sprung in place in a raggle and will lock itself therein upon an outward pull on the flashing.

13. A brick wall flashing comprising a plurality of fabric plies of different widths, one overlapping the others, a spring metal strip permanently connected to the meeting edges of the plies, the strip being V-shaped rounded outwardly at the ends, and insertable in a raggle, and means for securing the flashing in place to form a water proof raggle joint.

14. A flashing of the class described comprising a plurality of plies, one of relatively less tensile strength than the others and included between them, and one of the others being reenforced for additional tensile strength, in combination with spring metal fastening means permanently attached to the several plies along one edge of each of them, the said fastening means being bent for insertion and engagement in a raggle for holding the flashing in place.

15. The combination of a flashing composed of a plurality of plies of fabric, and a bendable metal strip permanently attached to the edge of the plies before applied to a wall, the outer edge of the strip being bent to engage in a raggle and in wood, and means to fasten the strip in place to engage the bent edge thereof.

CARROLL C. FIGGE.
